CLAIM

(21) Appl. No.: **29/270,923**

I claim the ornamental design for a ball and socket connector, as shown and described.

(22) Filed: **Jan. 5, 2007**

DESCRIPTION

(51) LOC (8) Cl. **08-08**

The claimed ornamental design for a ball and socket connector which embodies the design is for use in a multi-connector chain.

(52) U.S. Cl. **D8/382**

FIG. 1 is a front view of a connector with the claimed design. The connector is axially symmetric; and,

(58) **Field of Classification Search** 403/122,

FIG. 2 is a bottom view of the connector.

403/135; D8/382, 344, 333, 380

The portions in broken lines are shown to illustrate environment only and form no part of the claimed design.

See application file for complete search history.
